Attorney:

UNITED STATES PATENT OFFICE.

RALPH E. H. POMEROY, OF CANTON, OHIO.

PULVERIZING MILL.

Application filed January 18, 1923. Serial No. 613,346.

To all whom it may concern:

Be it known that I, RALPH E. H. POMEROY, residing at Canton, in the county of Stark and State of Ohio, a citizen of the United States, have invented or discovered certain new and useful Improvements in Pulverizing Mills, of which improvements the following is a specification.

In an application filed July 10, 1922, Serial Number 573905, is described and claimed a construction of pulverizing mechanism in which air for the removal from the pulverizer of particles reduced to the desired size is introduced at one end of the pulverizing drum, preferably adjacent to the inner periphery and escapes laden with dust from the same end of the drum. In the specific embodiment of the improvement described and shown in the above application, the air enters at a plurality of points around the periphery and flows inwardly towards the axis of the drum. The invention described herein has for its object the provision of means for determining the sectors of the drum at which the air will enter and leave the drum, the flow of air into and from the drum being in reverse directions as in the application above referred to. The invention is herein-after more fully described and claimed.

In the accompanying drawings forming a part of this specification, Fig. 1 is a perspective view of a pulverizer, embodying the improvements claimed herein, and Fig. 2 is a plan view of portions of the drum being broken away.

In the practice of the invention the drum in which reduction is effected, consists of a cylindrical casing 1 having one end closed by a head 2 protected against abrasion by end liners 2^a and having a hollow trunnion 3 through which material to be reduced is fed into the drum. Provision should be made for preventing the escape of fluid from the drum through the trunnion through which the fuel is fed to the drum. While any suitable means may be employed for this purpose, it is preferred to employ the construction shown in the application above referred to, which consists of a positively driven screw 4 arranged in the hollow trunnion to which the material is supplied from the hopper in such quantities as to maintain the trunnion fully charged. At its opposite end the casing 1 which is preferably made of sheet metal, has secured thereto a ring or tire 5 adapted to ride on rollers during the rotation of the drum, by a driven pinion engaging the annular toothed member 8 secured to the head 2 of the drum, as in the application above referred to. The casing serves as a retaining member for annular liners 9 so constructed as to form in connection with the casing a plurality of passages 10 extending longitudinally of the drum. The annular liners are retained in such relation to each other by suitable means that continuous passages are formed from end to end of the drum. These passages are closed at one end by the head 2. The annular liners are held within the drum by a head 11 secured to the casing and having openings 12 adjacent to the periphery of the head and adapted when the head is in position to register with the passages 10 of the liners. As it is desired that the fluid should flow from and into the passages 10 in directions approximately at right angles to the radii of the drum, the inner wall of the liners have approximately radial portions 13 through which are formed perforations 14. Attached to or made integral with the outer side of the head 11 are a series of radial vanes 42 spaced to form a number of channels radiating from the center and corresponding in number to the peripheral openings 12. The outer walls of these channels are formed by a hood 44 which has its one end attached to the rotating drum in any suitable manner and the opposite end is provided with an opening which registers with the inner open end of the distributing head B. This head is provided on one side with an inlet nozzle 35 for air and on the opposite side with an outlet nozzle 36 for pulverized material. Suitable means are employed for forming a tight joint between the hood 44 and the inner end of the head which is stationary. Within the distributing head is arranged an adjustable partition or shutter 37 whose axis of rotation coincides with the axis of the distributing head. This shutter extends the full length of the distributor dividing the interior into an inlet channel 38 and an outlet channel 39. In the construction shown these two channels are made of equal transverse dimensions but can be made of different transverse dimensions by changing the angular relation of the position of the blades of the shutter on opposite sides of its axis of rotation. In the construction shown, these wings or blades are at an angle of 180 degrees from each other. The portion of this shutter within

the distributing head is made adjustable by means of a shaft 40 and a crank 41.

In the operation of this improved pulverizer, the air will enter through the inlet ports 35, flow along the channel 38 on one side of the shutter and enter channels 43 and passing along the same, flow through the port 12 along the channels 10 and out through the perforations into the drum. The air flows 10 through the interior of the drum where it becomes laden with fine material and will leave the drum through ports 14 and passages 10 which are connected by channels to the outlet passages or channels 39 on the opposite side of the shutter.

It will be readily understood that by the adjustment of the shutter the air will be made to enter the drum through any desired sector and leave the drum through any other 20 desired sector, which sector may be so located that the air will have to pass through the charge contained in the drum before escaping through the ports 14 and passages 10.

I claim herein as my invention:

25 1. A pulverizing mill having in combination a drum, one of the heads provided with a plurality of ports, a distributing head provided with inlet and outlet passages communicating with said drum and adjustable 30 means for connecting the ports in communica-

cation with the drum with the passages in distributing head.

2. A pulverizing mill having in combination a drum having a plurality of ports at one end, a plurality of radial passages connected at one end to said ports, a distributing head communicating with the inner ends of said passages and provided with inlet and outlet passages communicating with said drum, and a shutter for controlling the connection of the passages in the head with the radial passages.

3. A pulverizing mill having in combination a drum provided with a plurality of passages extending longitudinally of the drum, a hood enclosing an end of the drum and spaced from the head of the drum, vanes interposed between the hood and the head of the drum forming radial passages communicating with the passages in the drum, a distributing head communicating with the inner ends of the radial passages, a movable shutter adapted to divide the head into two compartments, and supply and discharge pipes connected to the head at points on opposite sides of the shutter.

In testimony whereof, I have hereunto set my hand.

RALPH E. H. POMEROY.
